A. WILKS ET AL

CONTAINER FOR COSMETICS

Filed July 27, 1927

UNITED STATES PATENT OFFICE.

ANNA WILKS AND EDWARD SCHEIER, OF NEW YORK, N. Y.

CONTAINER FOR COSMETICS.

Application filed July 27, 1927. Serial No. 208,677.

This invention relates generally to cosmetic holders, and has more particular reference to a novel holder particularly adapted to hold lipstick, rouge, and powder.

5 The invention has for an object the provision of a holder which will conveniently hold certain cosmetics, and which can be manufactured and sold at a reasonable cost.

10 For further comprehension of the invention and of the objects and advantages thereof, reference will be had to the following description and accompanying drawing and to the appended claims in which the various novel features of the invention are more particularly set forth.

Referring to the accompanying drawing forming a material part of this disclosure:

Fig. 1 is a perspective view of an article constructed according to this invention, certain front parts being broken away to disclose interior parts.

Fig. 2 is a side view thereof in open position.

Fig. 3 is a plan view, looking along the line 3—3 of Fig. 2.

Fig. 4 is a perspective view similar to Fig. 1, but disclosing a modified form of the invention.

Fig. 5 is a perspective view, disclosing another modified form of the invention.

Fig. 6 is a side view similar to the central part of Fig. 2, but disclosing a modification thereof.

The reference numeral 10 indicates a flat 35 base from which vertical sides 11 project, and contained within the boundary of the sides is a powder container 12 containing powder 13. The container 12 has some splits 14 on its top face through which the 40 powder 13 may pass. A powder puff 15 rests on the top surface of the container 12.

A pipe member 16 is of such shape and size that the vertical sides 11 may slide therein, and a smaller pipe member 17 fits 45 into the top of member 16 and is pasted in position. A horizontal partition 18 is pasted across the bottom of member 17. A small partition wall 19 is secured on top of partition 18, and rouge 20 with rouge puff 21 is 50 arranged in this partition portion. Some lipstick 22 rests on partition 18. A cover 23 fits on the member 17.

It should be understood that the invention is not limited to the particular shape of the 55 article shown in Fig. 1, but may be of any

shape, as for example, Fig. 4 shows a square, and Fig. 5 a circular shape.

In use, when it is necessary to use lipstick or rouge, the cover 23 is removed so that the lipstick 22 and rouge 20 are available. The 60 powder 13 may be used by withdrawing the base 10 together with the attached sides, and the contained powder, and this powder may be applied by means of the puff 15.

The modification of the invention illustrated in Fig. 6 discloses the member 16' and 65 17' pasted to each other. The horizontal partition 18' has angle member 25 secured to the bottom thereof, and each angle member has an elongated slot 26 with serration 27 on 70 one side. Pins 28 project through slots 29 in the sides of member 16', and through the slots 26, while tension springs 30 normally urge the pins into engagement with the serrations 27. The height of the partition 18' 75 may be changed by manually disengaging the pins 28 from the serrations, moving the partition to the desired height, and then allowing springs 30 to re-engage the pins 28 in the serration, locking the partition as 80 placed.

While we have illustrated and described the preferred form, construction, and arrangement of the several elements employed, it will be understood that the device is, 85 nevertheless, susceptible of considerable modification therein, and we therefore reserve the right and privilege of resorting to all such changes as may be fairly embodied within the spirit and scope of the invention 90 as claimed.

Having thus described our invention, what we claim as new, and desire to secure by United States Letters Patent is:

1. An article of the class described comprising a base, vertical sides secured thereto, a powder package housed by the vertical sides, a puff on the package, a pipe member, the said vertical sides being engaged within the bottom of the pipe member, another 100 pipe member secured within the top of the first pipe member, a horizontal partition across the lower side of the second pipe member, rouge and lipstick positioned on the said horizontal partition, and a cover engaging 105 over the top of the second mentioned pipe member.

2. An article of the class described comprising a base, vertical sides secured thereto, a powder package housed by the vertical 110

sides, powder in the package, a puff on the package, a pipe member, the said vertical sides being engaged within the bottom of the pipe member, another pipe member secured within the top of the first pipe member, a horizontal partition, across the lower side of the second pipe member, rouge and lipstick positioned on the said horizontal partition, and a cover engaging over the top of the second mentioned pipe member.

3. An article of the class described comprising a base, vertical sides secured thereto, a powder package housed by the vertical sides, powder in the package, the top of the package having slits, a puff on the package, a pipe member, the said vertical sides being engaged within the bottom of the pipe member, another pipe member secured within the top of the first pipe member, a horizontal partition across the lower side of the second pipe member, rouge and lipstick positioned on the said horizontal partition, and a cover engaging over the top of the second mentioned pipe member.

4. An article of the class described comprising a base, vertical sides secured thereto, a powder package housed by the vertical

sides, a puff on the package, a pipe member, the said vertical sides being engaged within the bottom of the pipe member, another pipe member secured within the top of the first pipe member, a horizontal partition across the lower side of the second pipe member, and a cover engaging over the top of the second mentioned pipe member.

5. An article of the class described comprising a base, vertical sides secured thereto, a powder package housed by the vertical sides, a puff on the package, a pipe member, the said vertical sides being engaged within the bottom of the pipe member, another pipe member secured within the top of the first pipe member, a horizontal partition across the lower side of the second pipe member, means for adjusting the height of the horizontal partition, rouge and lipstick positioned on the said horizontal partition, and a cover engaging over the top of the second mentioned pipe member.

In testimony whereof we have affixed our signatures.

ANNA WILKS.
EDWARD SCHEIER.
